UNITED STATES PATENT OFFICE

WILLIAM D. LUCE, OF HAVERHILL, MASSACHUSETTS, ASSIGNOR OF ONE-HALF TO
JOSEPH E. DUBE, OF HAVERHILL, MASSACHUSETTS

AUTOMATIC DAMPER

Application filed March 17, 1930. Serial No. 436,323.

This invention relates to certain improvements in dampers which are primarily designed for use in connection with domestic heating furnaces, although adapted for use in larger fuel burning plants.

In the operation of oil burners in domestic furnaces, thermostatic control is usually employed, which acts to shut off the burner completely when a certain room temperature is attained, and then to turn the burner on to the fullest extent when the room temperature is lowered to another point, so that the burner is either operating to its full capacity, or is completely shut off. In view of the fact that ample provision for the supply of air to the burner, when in operation, must be made, in many installations the air inlet is constantly kept open, so that, after the burner is turned off, air will continue to pass up through the burner chamber and boiler and out through the chimney. This constant circulation of relatively cool air through the furnace not only carries away all the heated gases within the same, but has a marked cooling effect on the furnace walls and consequently on the heated air or water which it contains, and, where the air is supplied from the room in which the furnace is located, the heated air in the room will be drawn up through the chimney and, consequently, cold air from outside will be drawn into the room, resulting in a marked cooling effect on the building.

With a coal burning furnace, the action is somewhat similar, particularly when forced draft is employed, although ordinarily the heat loss due to the suction action of the chimney is usually somewhat less, as the air inlet to the furnace is usually controlled, but it is customary, particularly where automatic draft control is employed, to provide an air inlet check, which admits air to the smoke pipe from the room, and this results in drawing warm air from the room and, consequently, cool air into the room from outside, with consequent loss of heat.

While various devices have been produced in an attempt to avoid the loss of heat by the escape of heated air up the chimney in

the manner above referred to, these devices, so far as I am aware, have been either ineffective, or objectionably complicated.

The objects of my invention are to provide a device for automatically controlling the suction action of the chimney to which a furnace is connected, so that the smoke pipe will at no time be opened to a greater extent than is necessary to permit the escape of burning gases from the furnace, but which will not obstruct such escape to an extent sufficient to cause such gases to escape into the room in which the furnace is located, which is of simple construction and adapted to be manufactured at small expense, as compared with other devices for the purpose, and is adapted to be readily installed in any ordinary smoke pipe without difficulty, and effectively prevent the loss of heat due to the suction action of the chimney.

I accomplish these objects by providing a form of damper which is adapted to be inserted in a smoke pipe between the furnace and chimney, which is so arranged that, when the suction action of the chimney tends to draw the gases from the furnace at a more rapid rate than that at which they would be normally discharged therefrom, to permit the escape of the products of combustion, the external air pressure will cause the passage through the smoke pipe to be reduced correspondingly, so that the withdrawal of warm air from the furnace room and a more rapid circulation through the furnace than is necessary for the discharge of the products of combustion therein will be prevented.

For a more complete disclosure of the invention, reference is made to the following specification in connection with the accompanying drawings in which:

Fig. 1 is a side elevation indicating the manner in which a damper, embodying the invention, is installed.

Fig. 2 is a top plan view of the damper.

Figs. 3 and 4 are horizontal, central sectional views thereof taken at line *a—a* of Fig. 1 and showing the parts in different positions.

Fig. 5 is a cross sectional view, at line *b*—*b* of Fig. 3.

Fig. 6 is an elevation of the inlet end of the device.

Fig. 7 is a detail view of a stop which may be employed to limit the closing movement of the damper.

In the drawing a furnace 1, and a chimney or stack 2 are indicated, and are shown as connected by a cylindrical smoke pipe 3 which extends approximately horizontally, the particular embodiment of the invention shown being designed to be inserted between two sections of the smoke pipe and comprises a smoke pipe section 4, adapted to be thus interposed.

According to my invention, approximately one half of the section 4 is cut away between its ends, leaving cylindrical end portions adapted for connection with the sections of the smoke pipe 3. The opening formed in the side of the pipe section 4 is preferably included by a vertical plane which bisects the pipe longitudinal and two vertical planes which are disposed at right angles to the longitudinal plane and terminate therein.

The opening thus formed is enclosed by a casing which is connected to the pipe section 4 about said opening and comprises a top wall 5, bottom wall 6, both of which are disposed horizontally, and end walls 7 and 8 which extend vertically between the top and bottom walls, so that the entrance to the opening in the side of the pipe is square, or rectangular and is enclosed by horizontal and vertical walls.

A damper is provided which is adapted to close said opening in all positions thereof, and which comprises a rectangular shaped sheet metal plate 9, the width of which corresponds to the distance between the top and bottom walls 5 and 6 and the length of which to the distance between the side walls 7 and 8, so that it may be held in a position to close said opening. Said plate 9 is rigidly connected at one end to a metal shaft 10, which is mounted for rotation between a pair of pivot screws 11, threaded in brackets 110, secured to the top and bottom walls 5 and 6, in close proximity to the sidewall 7, the ends of said screws being conically formed to engage with the ends of said shaft in conical recesses therein at its axial line, so that they form step, or thrust bearings therefor. The plate 9 is thus permitted to swing horizontally with minimum friction about the axis of shaft 10. The width of the plate 9 is as nearly equal as practical to the distance between the top and bottom walls 5 and 6 and said screws 11 are so adjusted that the edges of the plate are held in close proximity to said walls, but without actual contact therewith, so that the plate may swing freely. Said plate 9 is

provided with an extension 12, of equal width, which extends outwardly therefrom in nearly right angular relation thereto and is cylindrically curved with relation to the axis about which these parts swing, the arrangement being such that the outer, or convex face of the extension 12 will swing in close proximity to a lip 80 on the outer portion of the opposite side wall 8, but without actual contact therewith, so that the swinging action of the plate will not be impeded.

By means of this construction the rectangularly shaped opening enclosed by the walls 5, 6, 7, and 8 will be practically closed by plate 9 and its extension 12 in all positions of the plate, which is arranged to swing from a position, in which it extends obliquely inward to approximately the middle of the pipe section 4, and closes approximately one-half the passageway through said section, as shown in Fig. 4, to a completely open position, in which it is held in parallel relation to the longitudinal central line of the pipe section, as shown in Fig. 3.

The damper plate 9 is also provided with an extension 14, which is secured to the inner side of the plate 9 and extends obliquely inward therefrom, the inner edge of said extension being so formed that when the plate 9 is in its innermost position, the edge of the extension 14 will engage the inner surface of the pipe section, so that the plate 9 and its extension 14 will practically completely close the passageway through the pipe section, it being understood that even in the closed position of these parts the construction will ordinarily and preferably permit a slight leakage past the same.

An arm 15 is rigidly mounted on the plate 9 and arranged to extend horizontally therefrom in opposite relation thereto past its axis and a counter weight 16 is adjustably mounted on said arm.

When the section 4 is placed in position between the adjacent sections of the smoke pipe it is preferably so set that the axial line of the shaft 10 is slightly inclined outwardly from the center line of the section, as it extends upwardly, as shown in Fig. 5, so that the gravity of the plate 9 and its extensions 12 and 14 tend to cause said plate to swing to its open position. This bias to swing to open position is counter balanced by the weight 16, which is adjusted to compensate for inaccuracies in setting up, so that the swinging movement of the damper may be practically unaffected by gravity. However, as a matter of safety it is considered preferably to adjust the weight so as to have the damper biased slightly to open by gravity, so that when the plate 9 is acted on by gravity only, it will swing to open position, but any slight action tending to swing it in

the opposite direction will cause it to swing to the closed position.

The outward swinging movement to open position may be limited by any suitable stop, but as constructed, the extension 14 will engage the inner side of the pipe section 4 and act as a stop to limit this outward movement. The inward movement may be limited by the engagement of the damper or plate 10 extension 14 with the inner side of pipe 4, or by the engagement of a lip 120 on the extension 12, or a set screw 18 therein, with the lip 80 on the wall 8. A lock may be provided to prevent movement of the plate 9 in either direction, the locking means shown 15 consisting of a latch or dog 17 mounted on the wall 8 near its outer edge and arranged to engage any one of a series of notches in the top edge of the plate extension 12, this being employed only when the automatic 20 operation of the device is not desired.

With the above described construction, while the damper is, as before stated, preferably so balanced that the action of gravity 25 tends slightly to swing it to the open position, it will be understood that but a slight force is required to swing it to closed position and hold it in this position. Also that, by pivoting the damper at one side of the 30 passage which it is adapted to close and arranging it so that it extends towards the outlet from its axis and swings towards the inlet as it closes to a position in which it extends obliquely across the passage, in the 35 direction of the normal flow of gas therethrough, from its axis, the damper will be adapted to act as a check valve, as gas forced from the furnace against the adjacent or inner side of plate 9 and extension 14 will tend 40 to swing the damper to open position, while gas forced in the opposite direction, or down the chimney will tend to swing it to closed position, so that down draft past the damper will be prevented. Furthermore, if there is 45 a suction action at the discharge end of the pipe 4 which reduces the pressure at the inlet end thereof below atmospheric pressure, the atmospheric pressure on the outer side of plate 9 of the damper will act to move the 50 damper towards its closed position, until these pressures are equalized.

Under normal conditions the operation of the damper is as follows: If the damper is employed in connection with an oil burning 55 furnace, in which the burner is operated at intervals when the burner is not operating, the pressure on the damper will usually act, for reasons hereinafter explained, to hold it in closed or nearly closed position. Under 60 such conditions, when the burner is lighted, there will immediately be a strong upward flow of highly heated gas into the smoke pipe and consequently a rapid increase of pressure against the inner, or furnace side of 65 the damper plate 9 and its extension 14,

which will over-balance the pressure against the opposite sides thereof, which are holding the damper in closed position, this pressure being principally the atmospheric pressure on the outer side of plate 9, thereby immediately forcing the damper to swing to its fully open position and permitting all products of combustion from the furnace to escape freely through the smoke pipe and up the chimney. These conditions will obtain so long as the burner is in operation, and will cause a heated column of gas to pass rapidly up the chimney, so that, when the burner is shut off and the pressure at the furnace side of the damper returns to normal, this rising column of gas will immediately cause a strong suction action in the smoke pipe, and will, unless prevented, draw cool air from the air inlet to the burner up through the furnace, and smoke pipe to the 70 chimney. The suction action of the chimney will, however, at once cause the pressure in the smoke pipe to be lowered below atmospheric pressure, so that, as the outer surface of the damper plate 9 is constantly 75 subjected to full atmospheric pressure, the pressure on the outer side of the plate will overbalance the pressure on its inner side and will cause it to swing inward until the pressure from the furnace against the inner side of the plate 9 and its extension 14 equals the inward pressure of the atmosphere on the outer side of the plate. As a result practically all the suction action of the chimney 80 on the furnace will be counter-balanced by 85 the inward atmospheric pressure on the damper, so that the damper will prevent this suction action from causing circulation through the furnace to a material extent. The withdrawal of the hot air in the furnace 90 will thus not only be largely prevented, but, what is more important, the continued circulation of cool air through the furnace, by the chimney draft, while the burner is 95 not operating will be almost wholly prevented thereby preventing a substantial loss 100 of heat. Ordinarily the slight leakage past the damper, when in fully closed position, which preferably is permitted, is sufficient 105 to permit the escape of products of combustion from the usual pilot flame which is kept burning, but any building up of pressure at the furnace side of the damper will cause the damper to be opened sufficiently to permit the escape of sufficient air or gas to 110 equalize the pressure. Ordinarily the suction action of the chimney, when the burner 115 is not being operated, will be sufficient to cause the damper to be held in closed, or nearly closed position.

With a coal burning furnace, the operation will be somewhat different, although in principle, it will be the same. That is, with such a furnace the escape of heated gas is much more nearly uniform, so that a con- 120

stant balance will be maintained between the inner and outer sides of the damper plate, which will cause the latter to be maintained in an intermediate position, which will be varied according to requirements. For example, if the draft is opened, or the coal door of the furnace is opened, the pressure at the furnace side of the damper will be increased, causing the damper to be opened, and when the draft is closed the damper will be closed by the external air pressure thereon, as before described, and the suction action of the chimney, when not desired, will be neutralized. The effect produced by opening an air check in the smoke pipe will thus be secured, without causing warm air to be drawn from the room in which the furnace is located, resulting in the prevention of loss of heat. The cross sectional area of the smoke pipe will thus be automatically maintained at a point sufficient to permit the escape of the products of combustion without substantially impeding the draft action of the furnace and, by adjusting the counter-weight 16 on the damper, so that the damper will be opened by gravity when the pressure in the smoke pipe is raised to, or above atmospheric pressure, any retarding action on the draft, when open, may be prevented. The ratio between the cross sectional area of the smoke pipe and the area of the side opening, which is constantly closed by the damper plate 9 and its extension 12, may be varied according to conditions, but ordinarily the area of the side opening will be made somewhat greater than the area of the smoke pipe. The effect of the difference in these areas may however be increased, wholly neutralized, or reversed by adjusting the counter-weight 16.

It will be understood that, while the smoke passage opposite the damper is shown as semi-cylindrical in cross section, the entire passage at this point may be made rectangular in cross section, in which case the form of the damper extension 14 will be correspondingly changed. Also, while the principles involved may be embodied in a construction which would operate in positions other than that shown, distinct advantages are secured by arranging the damper to swing about an approximately vertical axis, as the counter-balancing of the damper, so that practically the same force will be required to swing it in either direction in all positions, may be more easily accomplished than under any other conditions of which I am at present aware.

Various other changes may obviously be made without departing from the spirit and scope of the invention.

I claim:

1. An automatic damper for a furnace comprising a casing having a smoke passage therethru, adapted for connection at its in-

let end to the furnace and at its outlet end to a chimney, and having a side opening to said passage between the ends thereof, a damper plate arranged to be freely moved inwardly and outwardly in said side opening and to close said opening and be subjected to atmospheric pressure on its outer side and to the pressure at the inlet end of the passage on its inner side in all positions thereof, to permit said plate to be moved inwardly, or outwardly according to which of the pressures thereon over-balances the other, and means arranged to be actuated by said plate to close said passage as the plate is moved inwardly.

2. An automatic damper for a furnace comprising a casing having a smoke passage therethru adapted for connection at its inlet end to the furnace and at its outlet end to a chimney, and having a side opening to said passage between its ends, a damper plate arranged to swing freely inwardly and outwardly within said side opening and to close said opening and to be approximately balanced against the action of gravity in all positions thereof, and means movable with said plate arranged to close said passage as the plate is swung inwardly and to permit atmospheric pressure on the outer side of the plate to move the same to close the passage when it overbalances the pressure within the passage, and to permit the pressure at the inlet end of the passage to move the plate to open the passage when it overbalances the pressure against the outer side of the plate.

3. An automatic damper for a furnace comprising a casing having a smoke passage therethrough adapted for connection at its inlet end to the furnace and at its outlet end to a chimney, and having a side opening to said passage between the ends thereof, a damper plate arranged to be freely moved inwardly and outwardly in said side opening, and to close said opening and to be constantly subjected to atmospheric pressure on its outer side and to the pressure at the inlet end of said passage at its inner side in all positions thereof, and means carried by said plate arranged to reduce the transverse area of the passage as the plate is moved inwardly to permit said area to be varied according to the relative pressures on the opposite sides of said plate.

4. An automatic damper for a furnace comprising a casing having a smoke passage therethrough adapted for connection at its inlet end to the furnace and at its outlet end to a chimney and having a side opening to said passage between its ends, a damper plate mounted to swing freely inwardly and outwardly in said opening about an axis adjacent one side thereof, and to swing towards the inlet end of said passage as it swings inwardly, means on said plate, co-

operating with the sides of said opening, to close the opening in all positions of the plate, and means extending from the plate remote from its axis arranged to close said 5 passage as the plate swings inwardly, the opposite movements of said plate being approximately balanced against the action of gravity, to permit the same to be automatically positioned according to the relative 10 pressures against its outer and inner sides.

5. An automatic damper for a furnace comprising a casing having a smoke passage therethrough adapted for connection at its inlet end to the furnace and at its outlet 15 end to a chimney, and having a side opening to said passage between its ends, a damper plate mounted to swing inwardly and outwardly within said opening about an approximately vertical axis located adjacent 20 the sides of said opening next the inlet end of said passage and arranged to close said passage as it swings inwardly, and means on said plate cooperating with the sides of said opening and arranged to close the opening in all positions of the 25 plate.

6. An automatic damper for a furnace comprising a casing having a smoke passage therethrough adapted for connection at its inlet end to the furnace and at its outlet 30 end to a chimney, and having a side opening to said passage between its ends, a damper plate arranged to swing freely horizontally inward and outward within said 35 opening and towards the inlet end of said passage, to close the passage as it swings inward, cooperating means on said plate and on the sides of said opening to prevent the passage of air through said opening to 40 the passage on all positions of the plate and to permit the position of the plate to be controlled according to the relative pressures 45 on its outer and its inner sides.

7. An automatic damper for a furnace comprising a casing having a smoke passage therethrough adapted for connection at its inlet end to the furnace and at its outlet end to a chimney, and having a side opening to said passage between its ends, a damper 50 plate mounted on said casing to swing horizontally about an axis in proximity to the side of said opening next said inlet end from a position in which it closes said opening and permits full opening of said passage to 55 a position in which it closes said passage, the top and bottom sides of said opening being extended inward in proximity to the path of movement of the corresponding edges of said plate and the free end of said 60 plate having an extension cylindrically curved about said axis in cooperating relation with the adjacent side of said opening, to close said opening in all inner positions of the plate, whereby the extent to which 65 the passage is closed will be varied accord-

ing to the relative pressure on the inner and outer sides of said plate.

8. An automatic damper for a furnace comprising a casing having a smoke passage therethrough adapted for connection at its inlet end to the furnace and at its outlet end to a chimney, and having a side opening to said passage between its ends, said opening having horizontally disposed top and bottom walls and upright end walls, a 70 damper plate mounted to swing about a vertically disposed axis arranged in proximity to the end walls next the inlet end of said passage with its top and bottom edges in proximity to said top and bottom walls respectively and having an outwardly projecting extension at its opposite end from its pivoted end provided with a face formed cylindrically about said axis and arranged to be held in proximity to the end wall opposite said axis, to close said opening in all positions of said plate, and a passage restricting plate cooperating with and extending from said damper plate beyond said extension in position to close said passage 80 when said damper plate is swung into said passage to an oblique position with relation to the direction of the passage, to permit unbalanced pressure at the inlet end of the passage to force said plate outwardly 85 to open the passage and to permit unbalanced pressure on the outer side of said plate to force the plate inward.

9. An automatic damper for a furnace comprising a casing having a smoke passage therethrough adapted for connection at its inlet end to the furnace and at its outlet end to a chimney, and having a side opening to said passage between its ends, a 100 damper plate mounted to swing within said opening and across said passage about a vertically disposed axis at the side of said opening next the inlet end of said passage, between a position in which it closes said passage and a position in which the passage 110 is open, an arm mounted on said plate and extending horizontally therefrom and oppositely thereto with relation to said axis, a weight adjustably mounted on said arm to counter balance the gravity action on said 115 plate when the axis is slightly inclined from the vertical, and means on said plate cooperating with the walls of said opening to close the opening in all positions of said plate, to permit the plate to be positioned 120 according to the relative pressures on the inner and outer sides thereof.

10. An automatic damper for a furnace comprising a casing having a smoke passage therethrough, adapted for connection 125 at its inlet end to the furnace and at its outlet end to a chimney, and having a side opening to said passage between its ends, a damper plate mounted to swing horizontally within said opening and across said passage 130

about an axis located in proximity to the side of said opening next the inlet end of said passage and slightly inclined from the vertical, whereby the plate is biased to be swung by the action of gravity thereon from a position in which it closes said passage to a position in which the passage is open, an arm connected to said plate and extending horizontally at the opposite side of said axis therefrom, a counter-weight adjustably mounted on said arm to counter-balance the gravity action on said plate, and means on said plate cooperating with the walls of said opening to close said opening in all positions of said plate, to permit the plate to be positioned according to the relative pressures on its outer and its inner sides.

10 In testimony whereof, I have signed my name to this specification.
